PLATFORM SHOE SOLE

Beth Levine, 59 W. 12th St., New York, N.Y.

Filed Aug. 16, 1962, Ser No. 71,310

Term of patent 14 years

(Cl. D7—7)

FIG. 1

FIG. 2

FIG. 3

FIG. 4

I claim:

The ornamental design for a platform shoe sole, substantially as shown.
